UNITED STATES PATENT OFFICE.

GLENN H. WAYNE, OF WATERBURY, CONNECTICUT, ASSIGNOR TO SCOVILL MANUFACTURING COMPANY, OF WATERBURY, CONNECTICUT, A CORPORATION OF CONNECTICUT.

MACHINE FOR ROLLING SCREW THREADS.

Application filed August 30, 1923. Serial No. 660,061.

To all whom it may concern:

Be it known that I, GLENN H. WAYNE, a citizen of the United States, residing at Waterbury, county of New Haven, and State of Connecticut, have invented certain new and useful Improvements in Machines for Rolling Screw Threads, fully described and represented in the following specification and the accompanying drawings, forming a part of the same.

This invention relates to machines for rolling screw threads.

In the formation of screw threads by rolling, a round blank is caused to roll between two threading dies which have relative movement. These dies have complementary series of thread-forming teeth and during the travel of the blank between the dies the metal of the blank is upset into the form of a screw thread.

In the use of thread-rolling machines as heretofore known there has been a considerable loss due to products which have to be rejected because of inaccurate, or what is known commercially as "drunk" threads.

It is the principal object of the present invention to provide a machine for rolling screw threads such that the threads produced are uniformly accurate within the limits of deviation allowed by trade standards. As is more fully set forth herein-after, the inaccuracies referred to are due to what may be termed a slippage of the blank with respect to the dies. It is more particularly an object of the present invention to provide a thread-rolling machine so constructed as to compensate for this slippage and thus produce more accurate threads.

With this general object in view the invention consists in the combinations, details of construction and arrangements of parts which will first be described in connection with the accompanying drawings and then more particularly pointed out.

In the drawings—

Figure 1 is a plan view, with parts in section, of a thread-rolling machine constructed in accordance with the invention;

Figure 2 is an enlarged view of part of

the same, with parts broken away and in section;

Figure 3 is an end view looking in the direction of the arrow in Fig. 2, with parts in section;

Figure 4 is a sectional view (enlarged) taken on the line 4—4 of Fig. 2, looking in the direction of the arrow;

Figure 5 is a similar view showing more or less diagrammatically certain of the parts shown in Fig. 4 in a different position;

Figure 6 is a sectional view taken on the line 6—6 of Fig. 2; and,

Figures 7, 8 and 9 are exaggerated explanatory views of dies and blanks.

Referring to the drawings, the invention in its entirety includes two complementary dies for rolling threads on a blank which rolls between the dies as the thread is formed. The blank may be rolled between the dies by relative movement of the dies and the dies may conveniently be flat blocks, one block being reciprocated with respect to the other. Although capable of various constructions, in that here shown as an example, slidably in upper and lower tracks 11, 12 of a bed block 13 is a slide 14 having a die-carrying portion 15. This latter carries a flat, substantially rectangular die block 16 which rests on a ledge 15^a of the carrier 15 and is secured in place by means of clamps 17 and bolts 18. The outer vertical face of this die block has a series of teeth 19, hereinafter referred to. To reciprocate the die 16, as here shown as an example, secured to the slide 14 is the end of a pitman 20 driven from a disk 21 by a crank pin 22 mounted therein. Disk 21 is rotatably connected with a gear 23 meshing with a pinion 24 on a drive shaft 25. This shaft is rotated by a pulley 26 to which power may be applied in any suitable manner. As the drive shaft rotates the slide 14 is moved forward and back in its bed block thereby to cause endwise reciprocation of the die block.

Opposite the reciprocating die 16 is a complementary die. This latter is mounted to have a slight compensating movement,

hereinafter described, but as distinguished from the traveling movement of die 16, the second die is stationary. In the exemplification here illustrated, carried by a frame 5 or bed block 27 is a supporting block 28 located opposite the slide 14 and adjustably held in position by bolts 29. The block 28 has a ledge 28^a on which is supported a die carrier 30 which is held in place by clamps 10 31 and bolts 32. Mounted in the die carrier 30, in a manner hereinafter described, is a flat, substantially rectangular die block 33 located on a level with the die 16, as appears in Fig. 3. The outer vertical face of the 15 die block 33 is formed with a series of parallel teeth 34 running endwise of the block but at an angle to the longitudinal axis thereof (Fig. 4). The teeth 19 of die 16 are similarly arranged, the teeth of one die, 20 however, being opposed to the intervening grooves of the other, as appears in Figs. 3 and 7.

As will be understood by those skilled in the art, the angle of the die teeth with respect to the longitudinal axis of the die block; that is, with respect to the direction of travel of the blank, governs the lead of the thread formed on the blank. In the present embodiment the die blocks are so spaced apart that the tooth crests are separated by a distance less than, and the groove bottoms by a distance greater than, the diameter of that part of the blank that is to be threaded. As a result, the outside diameter of the formed thread is greater than was the diameter of the blank before threading. The embodiment shown is particularly adapted to threading cap screws and with the die relation shown, the blanks have an 30 enlarged stem so that when threaded, the outside diameter of the threads equals the diameter of the stem.

When the traveling die 16 is drawn back to the position of Fig. 1, a round blank 100 45 is placed between the adjacent ends of the dies by hand or by any suitable feeding means. Fig. 4 shows a cap screw blank having its polygonal head above the top edge of the die block, the block having a plain surface 35 corresponding to the stem 36 of the blank that is not to be threaded. Upon the advance movement of die 16, the blank is rolled between the two dies, that is, the blank revolves on its own axis and 50 travels along between the dies as the traveling die advances. For a half turn of the blank, the teeth of die 16 form thread portions in half the surface of the blank and the teeth of the die 33 form thread portions in the other half of the blank surface. That is, referring to Fig. 9 which 55 represents a section through the blank, die 16 for example, has formed thread portions from the point X around to point Y and die 33, during the same half turn of the

blank, has formed thread portions from Y around to X. During the next half turn of the blank the half threads formed by the die 16 are presented to die 33 and the half threads formed by the die 33 are presented to die 16 for further formation or finishing or both. Ordinarily the complete thread is roughly formed during the first half turn or first few half turns, the remainder of the action being in the nature of a finishing or planishing operation. As a result of the die action, by the time the traveling die has moved across and beyond the other die, the blank is formed with a complete finished thread and can drop out from the dies, to be removed in any suitable manner.

While screws have been threaded by rolling blanks between dies in the general manner above described, the threads on rolled screws as heretofore made, have not always been accurate. There has been a considerable loss due to so called "drunk" threads which will not enter the standard gauge. These "drunk" threads are due to a variation from the true or theoretical lead of the thread. In the ideal formation of rolled threads, the blank should start its axial movement and traveling movement, at the same instant and its axial and traveling movements should continue regularly and at the rate for which the dies are designed. It sometimes happens, however, that the start of the axial movement and the start of the traveling movement are not simultaneous, or the rate of movement is irregular. In other words, there is a certain amount of slippage of the blank with respect to the dies. As a result of this slippage, in machines heretofore known, the lead of the formed thread varies from the theoretical lead because that half of the thread formed by one die is out of true position when it moves around to the other die and consequently the teeth of the latter cause the thread to be distorted out of true.

Referring to Fig. 7, there is shown, diagrammatically and in exaggerated manner, the ideal conditions. A represents half of the blank and B represents one die. A' represents the same half of the blank after a half turn and C represents the other die. As Fig. 7 shows, each groove in the blank formed by the teeth of die A is in true registry or mesh with the corresponding teeth of die B and each thread-crest of the blank formed by the grooves of die A is in true registry or mesh with the corresponding groove of die B.

Fig. 8 shows similarly the result of slippage of the blank in the machine heretofore known. As in Fig. 7, A represents half the blank and B one die, C representing the other die and A' the same half of the blank after a half turn. At the right, the broken lines

indicate the teeth and grooves of the die, the full lines indicating the relative position of the blank after a half turn and upon slippage. That is, the groove *a*, under formation by tooth *b* of die *B*, when it reaches die *C* is not in true mesh with the tooth *c*, due to slippage, but has the position *d*. The same is true, as will be apparent, of all the grooves and crests. As a result of this out-of-true relation between die and thread, the thread will be distorted by the die *C* out of its true lead and the finished product will be inaccurate.

The present invention includes means for permitting a die movement transverse the direction of the blank's travel, thereby to compensate for slippage of the blank. This may be accomplished for example by so mounting the stationary or non-traveling die that it may float. Although capable of various constructions, in that here shown as an example, the die block 33 is carried by a bearing plate 40 which is slidable on the face of the die holder 30. As appears in Fig. 6, the holder 30 has rabbeted top and bottom ledges 41, 42, by which the plate 40 is confined, but enough clearance is left to permit a slight movement of the die. As shown, the die is pivotally mounted, the pivot being adjacent the end of the die at which the blank starts. To this end, secured to the inner face of the plate 40 is a pivot pin 43 mounted to swivel in a suitable hole in the die carrier 30. The die block and its bearing plate can thus swing about pin 43 as a pivot, the slightly curved end of the die block bearing against a roller 44.

When and if slippage of the blank occurs, and conditions such as described in connection with Fig. 8 exist, the slippage is compensated for by movement of the die 33 about its pivot, the free end of the die moving across the direction of travel of the blank. That is, when the thread of the blank leaving die 16 and approaching die 33 fails to mesh properly with the latter, the strains set up, instead of distorting the thread of the blank to give it an inaccurate lead, cause the die 33 to swing on its pivot to permit the thread and die teeth to have accurate registry or mesh. In other words, the die changes its relative position to compensate for the change in the relative position of the blank, and as a result the thread is not distorted.

With the construction described the threads produced on a succession of blanks are uniformly accurate within the limits of deviation allowed by trade standards.

It is desirable to have the floating die in normal position at the start of the rolling of the blank and during the first part of the blank travel. The invention in its entirety, therefore, includes means for resetting the die to normal or initial position,

if it has moved, and locking it in such position for a predetermined period with respect to the blank travel. Although capable of various constructions, in that here shown as an example, the end of the bearing plate 40 has a wedge-shaped notch 50 adapted to be entered by a wedge 51. This wedge is formed on the end of a plate 52 slidable in a guide housing 53 on the die carrier 30. On the other end of the plate 52 is an arm 54 through which passes a rod 55 slidable in an open-sided bracket 56. On the outer end of rod 55 is a nut 57 and between the nut and arm 54 is a coiled spring 58. When the rod 55 is pulled in the direction in which wedge 51 points (to the left in Figs. 4 and 5), the force of spring 58 causes movement of arm 54, whereby the wedge is moved toward the notch 50. Upon resistance being encountered by the wedge, spring 58 is compressed until, the coils being closed, nut, spring and arm move as a unit to force the wedge completely into the notch. During this movement, if the die unit, which includes plate 40, has moved out of normal position, the wedge 51 acting against the side of notch 50 cams the die unit back to normal position. Further, it will be observed, as long as the wedge remains in the notch the die unit is locked against movement. This position is shown in Fig. 4.

While the means for actuating the rod 55 may be varied, it may conveniently be accomplished by the movement of the traveling die and may make possible a release of the wedge after a predetermined die travel. Although capable of various constructions, in the present embodiment, secured to the forward end of the die carrier 15 is a bracket 60 having an arm 61 extending toward die 33 (Figs. 2 and 3). This arm is bent to have its end parallel with and above die 33 and this end 62 is provided with a slot 63. Set in the slot 63 by means of a nut 64 is a pin 65 carrying a roller 66. During the idle back stroke of the traveling die, the roller 66 engages an elongated lever 67, fulcrumed on the die carrier 41 and pinned to the end of rod 55. When the wedge 51 is in release position the lever 67 has the position shown in broken lines (Fig. 4), the roller being similarly indicated. As the roller advances to the left it pushes down the lever whereby the rod 55 is given the movement above described and the wedge is forced into the notch 50 to re-set the die if it is moved. Not only is the die re-set in normal or initial position, but it is held locked in such position as long as the lever is held down by the roller.

As soon as the traveling die has moved a predetermined distance on the operative advance stroke, the die 33 is released from

its lock so as to be able to float as described. To this end, in the exemplification shown, there is provided means for giving a reverse movement to rod 55 and thus withdrawing the wedge from its notch.

As here shown as an example, coiled about the rod 55 is a spring 69, its ends being confined between bracket 56 and a collar 70 fastened to the rod 55. Upon locking movement of the rod, this spring is compressed. As soon, therefore, as lever 67 is released by roller 66, spring 69 re-expands and moves the rod 55 back to former position (to the right in Figs. 4 and 5). The rod moves alone until collar 70 makes engagement with arm 54 but thereafter this engagement causes a simultaneous movement of the arm to withdraw wedge 51 from notch 50. During this movement of rod 55, spring 58 is free to re-expand to its former position. A collar 70^a, pinned to rod 55, acts as a stop against bracket 56 to limit the release movement of the rod. This position of the parts is shown in Fig. 5, in which, for simplicity of illustration, the teeth of die block 33 have been omitted.

If it is desired to vary the time, with respect to the travel of the die 16 and blank, at which the die 33 is permitted to float, the pin 65 may be moved along its slot. By this adjustment, the lever 67 will be released earlier or later with respect to the start of the operation, as may be desired.

The dies here illustrated are for forming right hand threads and the compensating movement of the floating die is upward, that is, toward the head of the blank. The invention in its entirety includes means for preventing a transverse die movement under the force of gravity. This means may conveniently be yieldable upon a predetermined force so that the die may have a compensating movement downward in case die blocks for a left hand thread are used.

Although capable of various constructions, in the embodiment shown, on the bearing plate 40 is a housing 71. In this housing is a plunger 72 each end of which extends through the end of the housing (Fig. 4). Coiled about plunger 72 is a spring 73 one end of which bears against the housing, the other end against a collar 74 on the plunger 72. The lower end of plunger 72 in normal position engages the bottom ledge 42 of the die carrier 30. Any tendency of the die block to move down by gravity is resisted by the spring 73. Should there be sufficient force applied, however, to overcome the force of spring 73, the die block can move downward against the compression of the spring. Thus, if left handed threads are being rolled the die can have a

compensating movement, in this instance downward.

The operation of the machine shown will be clear from the above without further description.

What I claim is:

1. The combination with two dies for rolling threads on a blank which rolls between the dies as the thread is formed, of means for permitting a die movement transverse the direction of travel of the blank, said movement compensating for slippage of the blank with respect to the dies during the thread forming operation, whereby accuracy in forming the thread is increased, and means for re-setting the die, after such compensating movement, in an initial position.

2. In combination, two dies for rolling threads on a blank which rolls between the dies as the thread is formed, means for moving one of said dies with respect to the other to cause rolling of the blank between the dies, means for mounting the other die to be movable transverse the direction of travel of the blank, and means for re-setting the second die in an initial position after any such transverse movement.

3. In combination, two dies for rolling threads on a blank which rolls between the dies as the thread is formed, means for reciprocating one of said dies with respect to the other to cause rolling of the blank between the dies on the advance stroke, means for mounting the other die to be movable transverse the direction of travel of the blank, and means operated by the movement of the first die on its return stroke for re-setting the second die in initial position.

4. In combination, two dies for rolling threads on a blank which rolls between the dies as the thread is formed, and means (a) for permitting a die movement transverse the direction of travel of the blank during a part of the blank movement, said die movement compensating for slippage of the blank with respect to the dies, and (b) for preventing said die movement during the first part of the travel of the blank.

5. In combination, two dies for rolling threads on a blank which rolls between the dies as the thread is formed, means for causing relative movement between the dies, means for mounting at least one die to be movable transverse the direction of travel of the blank, and means dependent on the relative position of the two dies for locking the transversely movable die against such movement and for releasing it before the termination of the passage of the blank between the dies.

6. In combination, two dies for rolling threads on a blank which rolls between the dies as the thread is formed, means for mov-

ing one die with respect to the other to cause the blank to roll between the dies, the second die being mounted for a die movement transverse the direction of travel of the blank, locking means for holding the second die against such transverse movement, and means for causing said locking means to release the die after a predetermined travel of the first die.

10 7. In combination, two dies for rolling threads on a blank which rolls between the dies as the thread is formed, means for reciprocating one die with respect to the other to cause the blank, on the advance stroke, to roll between the dies, the second die being mounted for a die movement transverse the direction of travel of the blank, and means including a part moving with the first die, for (a) resetting the second die in initial position upon the idle return stroke of the traveling die, (b) locking the second die in initial position, and (c) releasing the die from its lock upon a predetermined travel of the reciprocating die upon its advance stroke.

25 8. In combination, two dies for rolling threads on a blank which rolls between the dies as the thread is formed, means for reciprocating one die with respect to the other to cause the blank, on the advance stroke, to be rolled between the dies, the second die being mounted for a die movement transverse the direction of travel of the blank, and means including a part moving 30 with the reciprocating die, for (a) resetting the second die in initial position upon the idle return stroke of the traveling die, (b) locking the second die in initial position, and (c) releasing the die from its lock upon a 35 predetermined travel of the reciprocating die upon its advance stroke, a part of said resetting, locking and releasing means being adjustable to vary the time with respect to the die travel at which the second die 40 is released.

45 9. In combination, two dies for rolling threads on a blank which rolls between the dies as the thread is formed, means for causing relative movement between the dies 50 to cause a blank to be rolled between them, means for mounting one die to have a movement transverse the direction of travel of the blank, and means for causing said die to be locked against such transverse movement during a variable portion of the blank-rolling relative movement of the dies.

55 10. In combination, two dies for rolling threads on a blank which rolls between the dies as the thread is formed, a movable die carrier for one of said dies, a stationary die carrier, a die unit comprising the second die mounted in said stationary carrier to have a movement transverse the direction of travel of the blank, said die unit and its

carrier having the one a wedge and the other 65 a wedge-shaped notch, and means for causing relative movement between said wedge and notch to place the same into and out of interlocking relation.

11. In combination, two sides for rolling 70 threads on a blank which rolls between the dies as the thread is formed, a movable die carrier for one of said dies, a stationary die carrier, a die unit comprising the second die mounted in said stationary carrier to 75 have a movement transverse the direction of travel of the blank, said die unit having a wedge-shaped notch, a wedge shaped to fit said notch and carried by the die carrier, and means for moving the wedge into and 80 out of the notch.

12. In combination, a movable die carrier, a die block mounted therein, a stationary die carrier, a die unit, comprising a second die block, mounted in said stationary die carrier to have a movement transverse the direction of travel of the blank, said die unit having a wedge-shaped notch, a wedge shaped to fit said notch, a lever, an operative connection between said lever and the wedge, a spring for normally holding said wedge out of the notch, an element moved by the movable die carrier for engaging said lever to cause the wedge to be moved into the notch, and means for moving the 85 movable die carrier to cause a blank to be 90 rolled between the dies.

13. In combination, a movable die carrier, a die block mounted therein, a stationary die carrier, a die unit, comprising a die block, mounted in said stationary die carrier to have a movement transverse the direction of travel of the blank, said die unit having a wedge-shaped notch, a wedge shaped to fit said notch, a lever, an operative connection between said lever and the wedge, a spring for normally holding said wedge out of the notch, an adjustably positioned element moved by the movable die carrier for engaging said lever to cause the wedge to 100 be moved into the notch, and means for moving the movable die carrier to cause a blank to be 105 rolled between the dies.

14. In combination, two dies for rolling 110 threads on a blank which rolls between the dies as the thread is formed, means for causing relative movement between the dies to cause a blank to be rolled between them, one die being mounted to be movable transverse the direction of travel of the blank, and means whereby the last named die may 115 be held against such transverse movement at the start of and during a predetermined portion of the blank-rolling relative movement of the dies.

In testimony whereof, I have hereunto set my hand.

GLENN H. WAYNE.
